UNITED STATES PATENT OFFICE.

ERNST O. SCHNELL, OF CHICAGO, ILLINOIS.

PAD FOR HAIR WAVING.

Application filed October 14, 1926. Serial No. 141,475.

This invention relates to improvements in pads for hair waving, and more particularly to the so-called steam pads used in the process of permanent hair waving.

5 The process of permanent hair waving involves the application of heat to the hair, strands of which are tightly wound or coiled about metal rod-like curlers, and subjected to heat in the presence of some hair treatment 10 preparation calculated to give permanency to the wave. Some methods use an alkaline liquid such as ammonia, and others use the so-called steam pads containing a solid alkaline substance, such as borax, the 15 particular function of each being the generation of an alkaline steam which penetrates the hair and produces the degree of permanency required. The objection to these methods and to all methods now in 20 vogue, is the attendant danger of devitalizing the hair, due to excessive application of heat and as a consequence, the hair becomes brittle and discolored. As a result, therefore, the practice of permanent hair waving 25 requires extreme care and expertness on the part of the operator.

In order that the general method of permanent hair waving will be understood, it consists of wrapping the hair treating substance tightly about the strand of coiled hair, whereupon a tube of pasteboard is passed over the pad and finally a tubular heating coil is passed over the pasteboard tube.

35 Of the two methods mentioned, the steam pad method is the one more extensively used, wherein the pads consist usually of borax in thin cake form wrapped in an envelope of cheesecloth or like fabric, the 40 envelope being stitched to enclose the borax cake. But since the nature of the borax is such that it readily crumbles in dried form, this form of pad is not satisfactory for the reason that the substance tends to 45 shift in the envelope and to sift through the meshes of the cloth and the perforations along the lines of stitching, in spite of efforts to make the pads sufficiently stable for shipment, such as lines of stitches to 50 divide the pads into sections and reinforcing the cake with a woven material.

So too, the present method of manufacturing steam pads is open to objection due primarily to difficulty in stitching the envelope, which is done with the hair treating

substance in a wet state, and this is a tedious and laborious operation. Moreover, the pads thus made are frequently imperfect, portions of the substance being exterior to the line of stitching, with the result that on 60 the application of heat, it escapes from the envelope and lodges in the hair and on the scalp with painful results.

The purpose, therefore, of the present invention is to provide a steam pad which 65 will overcome all of the objections herein mentioned, and involving an entirely new construction or formation of the finished pad.

The following, therefore, constitutes a preferred embodiment of my invention, reference being had to the accompanying drawings, in which

70 Figure 1 is a perspective view of a preferred form of steam pad with one end portion opened to show the method of construction.

75 Figure 2 is a cross-sectional view of the pad taken on line 2-2 of Figure 1.

80 Figure 3 is a cross-sectional view taken on line 3-3 of Figure 1.

85 Figure 4 is a perspective view of a modified construction for the steam pad; and

Figure 5 is a cross-sectional view of the 85 pad taken on line 5-5 of Figure 4.

Inasmuch as the chemical and physical make-up of the hair treating substance is an important feature of the invention, regardless of the form in which it is finally prepared for use in the hair waving process, 90 I will first disclose its composition.

In general, the hair treating substance consists of an emulsified oil, mixed with a salt which when dissolved in water, shows a weak alkaline reaction, and a filler, the composition being initially prepared in a high plastic paste form.

95 The emulsified oil consists of a suitable vegetable, animal or other non-drying oil, an emulsifying agent, such as a suitable grade or kind of colloidal clay, and water, as the vehicle for the emulsification. By preference, I use either olive oil or castor oil and colloidal clay of the bentonite (wilkenite) type. To form the emulsion, I take 25 parts by weight of olive oil, 5 parts by weight of bentonite (wilkenite) and 70 parts by weight of water, although the proportions may be varied somewhat from those given. These ingredients are thoroughly mixed to- 110

gether so that the oil is in the internal phase and the colloidal clay and water are in the external phase.

The emulsion having been prepared, a 5 paste is then formed consisting of about 20 parts of the emulsion, 60 parts of a relatively weak alkaline salt and 20 parts of a filler, such as silica of say, 200 mesh fineness. One of several salts may be used, or 10 a mixture of two or more salts, of which the following are examples: disodium phosphate; sodium pyrophosphate; sodium bicarbonate; ammonium bicarbonate; and/or sodium and ammonium phosphate.

15 In carrying out the compounding of the substance commercially, an ordinary tank mixer with agitating paddles is used in which the emulsion is prepared. Warm water and bentonite are first mixed together 20 to form a creamy homogeneous liquid, to which is added warm oil which becomes thoroughly combined with the aqueous dispersion of the clay to form the emulsion. This emulsion is very stable, and hence the 25 separating of the oil from the suspending liquid is very slow. Consequently, large quantities of the emulsion can be prepared and stored for use as needed, since but slight agitation is required to re-establish its original 30 creamy uniform consistency.

The emulsion which may either be taken directly from the mixing tank or from the stored supply, is mixed and thoroughly kneaded with the alkaline salts and filler in 35 the proportions already stated, into the form of a highly plastic paste or butter consistency. In this form it is then formed into bricks of convenient size, and thence sliced into thin cakes or slabs, either by knife, 40 wire or other slicing means. It is in the form of these thin cakes or wafers that the hair treating substance is enclosed within the fabric envelope, as will presently be described in connection with the drawing.

45 As thus compounded and utilized in steam pads, the hair treating compound possesses certain chemical and physical properties calculated to insure results hitherto not obtainable in the materials and methods used.

50 When the pads containing the substance herein disclosed are moistened and applied to the hair in the manner described, the application of heat causes an alkaline steam to be generated which penetrates the hair and 55 imparts the permanency to the wave. Accompanying the alkaline steam is also generated actual oil steam which also penetrates the hair and protects it against the excessive action of the alkaline steam and heat 60 on the hair structure, the tendency of which, if not perfectly regulated, is to destroy the hair, leaving it lifeless, brittle and discolored. The presence of the oil steam, therefore, makes the hair soft, pliable and lustrous, at the same time counteracting the

destructive action of the alkaline steam on the hair if allowed to continue too long. It therefore removes from the operation that element of uncertainty as to time of heat application, which is particularly difficult to cope with, regardless of the care and experience of the operator, owing to the difference in texture of the hair of different individuals, as well as in different parts of the scalp of the same individual.

75 It follows, therefore, that by the use of steam pads containing the hair treating substance herein disclosed, satisfactory results can be assured even in the hands of less experienced operators. Similarly, hair of 80 light shades and dyed hair, which are particularly susceptible to discoloration, can be waved without difficulty, in fact, in the treatment of dyed hair, the dye is not only preserved, but becomes more permanently fixed 85 thus imparting new life and lustre into the hair.

90 The results thus obtainable with the hair treating substance, may be attributed to the fact that while the steam works under the scale of the hair, the presence of the oil steam prevents the alkaline steam from attaching the body of the hair, with the disastrous results already described.

95 The physical properties of the substance are also of importance as compared with the loose and powdered form of the ordinary borax steam pads now in use. In the first place, the presence of bentonite, not only acts as an emulsifying agent, but also as a 100 plasticizing and bonding agent which unites the entire mass into a porous structure which does not crumble when dry and gives it highly plastic properties when moistened, allowing a close contact with the hair. 105 Moreover, the substance has inherent adhesive properties, increased viscosity when heated and decreased expansion, all of which add greatly to ease of application and the elimination of many of the trying aspects 110 of the present hair waving treatments. Finally, the physical properties of the substance is such that when enclosed in a fabric envelope, it provides a leakproof pad which may be shipped and handled without the 115 crumbing of the substance and its sifting through or shifting in, the envelope.

120 Referring now to the steam pads as preferably constructed, they are generally flat rectangular envelopes 1 of cheesecloth, flannel or the like, in which is enclosed a thin wafer 2 of the hair treating substance. The pads are rectangular in shape and, roughly, four and one-half inches in length and two or two and one-half inches in width. In 125 making the pad shown in Figure 1, a sheet of the fabric is folded around the wafer 2 and lengthwise thereof with its margins overlapping each other midway of one face of the wafer for a distance of one-half inch 130

or so, with portions extending beyond the ends of the wafer of about the same length. These overlapping marginal portions are then sealed together by applying a heat-resisting adhesive between the contacting surfaces, thus entirely enclosing the wafer. Any suitable heat resisting adhesive may be used for sealing the envelope, although preferably one composed of a mixture of sodium silicate, casein and glycerine is particularly suitable for the purpose. In sealing the envelope, it is preferred to leave a space of one-eighth of an inch or so at each end, separating the edge of the wafer from the sealed edge of the envelope so as to allow room for the wafer to expand when moistened and heated. Applied to the envelope and on the face thereof having the sealed edge, is a moisture-proof sheet 4 of waxed paper, oiled silk, or like material, having the same dimensions as the envelope and secured thereto by the same adhesive used in sealing the edges of the fabric together, and which is applied along the end or narrow edges of the envelope.

The pad shown in Figure 2 is similarly made, except that the fabric envelope 5 is folded double to enclose the wafer 6, with the free edges of the fabric brought together in lapping relation and glued together by a band of adhesive of about one-fourth of an inch in width extending around the three open sides of the envelope. In applying the adhesive, provision is made for a free space about the edges of the wafer to permit of expansion of the substance, although the method of manufacture is quite the same as already described.

These pads thus constructed are ready for use, the same being first moistened and then wrapped around the strand of coiled hair, with the layer of waterproofing material outermost. The remaining step in the process is to enclose the pad in a suitable heat-resisting tube or casing, which in turn is surrounded by a heating element, the heat being transmitted through the walls of the casing to generate the alkaline and oil steam which function in the manner already described, to impart the so-called permanent wave into the hair thus treated.

The advantage of this method of manufacture of the steam pad lies primarily in

the decreased cost of production by the elimination of the stitching operation, and 55 the substitution of the gluing operation, the former being especially difficult when the materials are wet, aside from the probability of excluding portions of the hair treating substance outside of the line of stitching 60 unless considerable care is used by the operator.

Having thus disclosed the novel features of my invention, I claim:

1. A steam pad for the purpose described, 65 comprising a hair treating substance in wafer form, a fabric envelope enclosing said wafer, and having its open edges sealed with a heat-resisting adhesive.

2. A steam pad for the purpose described, 70 comprising a sheet of woven fabric folded about a thin mass of hair treating substance with its edges overlapping to completely enclose said mass, and a heat-resisting adhesive applied between the edges of said fabric. 75

3. A steam pad for the purpose described, comprising an envelope of fabric enclosing a thin wafer of hair treating substance, and sealed at its edges with a heat-resisting adhesive of sodium silicate, casein and glycerine. 80

4. A steam pad for the purpose described comprising a thin wafer of relatively flexible hair-treating substance, and a covering for said wafer consisting of a sheet of fabric 85 folded around said wafer, with two of its edges overlapping on one face of said wafer, its remaining edges projecting beyond the transverse edges of said wafer in overlapping engagement, said overlapping edges 90 being sealed together with a heat-resisting adhesive.

5. A steam pad for the purpose described comprising a thin wafer of hair treating substance, an envelope for said wafer consisting of a sheet of fabric folded around said wafer with the marginal portions of said sheet meeting in overlapping contact beyond the edges of said wafer, and sealed together with heat-resisting adhesive, and a 95 sheet of moisture-proof material applied over one face of said envelope and secured thereto by said adhesive. 100

Signed at Chicago, Ill., this 12th day of October 1926.
